SNOWMOBILE TRANSPORTATION DOLLY

Frank W. Mayer, 1956 Cedar Drive,
Grafton, Wis. 53024

Filed Oct. 13, 1967, Ser. No. 8,994

Term of patent 3½ years

Int. Cl. D12—03, 13

U.S. Cl. D14—3

FIGURE 1 is a top, side and front perspective view of a snowmobile transportation dolly embodying my new design; and

FIGURE 2 is a top, rear and side perspective view of the dolly taken from the other side thereof.

I claim:

The ornamental design for a snowmobile transportation dolly, as shown.
